[57] CLAIM

The ornamental design for a female coupling and seal unit, as shown and described.

DESCRIPTION

FIG. 1 is a side elevational view of a female coupling member and seal showing my new design;

FIG. 2 is a side end elevational view taken from the left of FIG. 1; and

FIG. 3 is a perspective view thereof.

The side of the female coupling member and seal opposite from that shown in FIG. 1 is the same as that shown in FIG. 1.

Fig. 1.

Fig. 2.

Fig. 3.
